UNITED STATES PATENT OFFICE.

WILLIAM R. MCCOMAS, OF OAKLEY, ASSIGNOR TO CRANE, BREED & CO., OF CINCINNATI, OHIO.

DESIGN FOR A COFFIN-HANDLE.

SPECIFICATION forming part of Design No. 12,018, dated November 9, 1880.

Application filed August 21, 1880. Term of patent 7 years.

To all whom it may concern:

Be it known that I, WM. R. MCCOMAS, of Oakley, in the county of Hamilton and State of Ohio, have originated a new Design for Coffin-Handles, of which the following is a full, clear, and exact description, reference being had to the accompanying drawing, making part of this specification.

The invention, as represented in the accompanying drawing, I describe as follows:

It consists of a design for a socket of a knuckle-joint coffin-handle.

The socket A, in general shape, is a geometrical figure, the outline being made up of arcs of circles of various radii and ornamented with a V-shaped matted figure.

The ornamentation further consists of a cir-

cular wreath of laurel-leaves, B, from the inside edge of which radiates toward the center a fan-shaped figure composed of points, rays, and dots C C. The upper and lower portions of the socket D D are ornamented with Egyptian plumes inclosed in a semicircle. The sides E E are composed of curved bands ornamented with leaves, points, and semicircular figures, mainly Japanese in style.

What I claim as new, and desire to secure by Letters Patent, is—

The design of a socket or ear of a coffin-handle, as shown and described.

WM. R. MCCOMAS.
